UNITED STATES PATENT OFFICE.

EINAR HANSEN, OF RJKAN, NORWAY, ASSIGNOR TO NORSK HYDRO-ELEKTRISK
KVAELSTOFAKTIESLSKAB, OF CHRISTIANIA, NORWAY.

APPARATUS FOR EFFECTING A CONTINUOUS CRYSTALLIZATION FROM SOLUTIONS.

1,273,058.

Specification of Letters Patent. Patented July 16, 1918.

Application filed September 8, 1915. Serial No. 48,785.

To all whom it may concern:

Be it known that I, EINAR HANSEN, a subject of the King of Norway, residing at Rjukan, Norway, have invented certain 5 new and useful Improvements in Apparatus for Effecting a Continuous Crystallization from Solutions; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of 15 this specification.

This invention has for its object an apparatus for effecting a continuous crystallization from solutions.

Various constructions of apparatus have 20 been proposed for the purpose of effecting a continuous crystallization from solutions while maintaining the solution in motion. Thus for this purpose one has employed the socalled rocking pans, which are maintained in rocking motion during the crystallization so that the precipitated crystals are moved alternately toward one side and the other.

Further it has been proposed to maintain 30 the mass in motion during the crystallization by means of rotating or oscillating stirrers.

The crystallizer constructed according to the present invention differs from other 35 known crystallizers by being of a very simple construction as well as regards the whole arrangement as also with regard to the mechanism for imparting the necessary motion to the apparatus and to the means 40 for effecting the cooling of the apparatus.

An embodiment of the invention is illustrated in the accompanying drawing in which Figure 1 is a diagrammatical side view of an apparatus constructed in accordance with the invention.

Fig. 2 is an end view of the apparatus.

The crystallizer vessel consists of a cylinder 1 which occupies an inclined position and which is quite open at the lower end 50 at 2, while at the upper end it is in part closed by means of a wall 3. This wall has a central opening through which the supply pipe 4 for the saturated solution is passed into the vessel. Below the lower 55 end of the cylinder is provided a funnel 5

into which the crystal mass flows and from which it is transferred to centrifugal machines or other apparatus, where the crystals are separated from the mother liquor.

The cylinder rests on rollers 6 connected 60 to spur gears and is provided at its ends with toothed rims 7 engaged by said spur gears. The rim at the upper end engages a toothed wheel 8 on the shaft 9 the rotation of which causes the cylinder to rotate 65 about its own axis.

Above the cylinder 1 is provided a perforated pipe 10 for cooling water, which is sprayed over the outer surface of the cylinder, flows down along this latter and is 70 taken up into a stationary tray 11, provided with outlet 12. Above and below that part of the cylinder, where the water from the pipe 10 flows on to the cylinder, collars 13 and 14 are provided, which prevent cooling 75 water from flowing outside of the tray 11. During the operation the crystallizer cylinder is maintained in a continuous rotating motion. The direction of this rotation may however be reversed from time to time, 80 when this is found suitable.

The interior of the cylinder is provided with stationary scrapers, serving to remove the crystals from the cylinder wall. In the example illustrated the scraper comprises a single bar 16 suspended by means of chains 17 from a supporting or adjusting shaft 18, which may be rotated to adjust the bar by a suitable handle.

The concentrated solution is continuously supplied through the pipe 4, the quantity supplied being regulated by means of a cock 15. On its passage through the cylinder the solution will move along a helical path on the cooled interior wall of 90 the cylinder toward the discharge opening 2. The inclination and the velocity of the cylinder, which should be adjustable are in each case so adjusted in accordance with the character of the treated solution, that the 95 crystallization process is finished when the mass reaches the discharge end of the cylinder. If it is found suitable the inner wall of the cylinder may be provided with annular intermediary walls which to a certain 100 degree effects a retardation of the motion of the mass toward the outlet. Such a wall may also be arranged at the outlet end of the cylinder. The supply of cooling fluid to the surface of the cylinder may also be 105 110

effected in other manners than illustrated for instance by a partial immersion of the cylinder into a vessel containing the cooling fluid.

5 1 claim:

1. Apparatus for effecting continuous crystallization, comprising an inclined, cylindrical crystallizer vessel, means to rotate the same, means to continuously supply material to its upper end, means continuously discharging from its lower end, means to supply a cooling spray exteriorly of the vessel means below said vessel to collect and discharge the cooling medium, a scraper mounted in the vessel and adjustable with respect to the interior thereof.

10 2. Apparatus for effecting continuous crystallization, comprising an inclined, cylindrical crystallizing vessel, means to ro-

20 tate the same, means to continuously supply material to the upper end of said vessel, means to permit a continuous discharge from the lower end of said vessel, means to supply a cooling spray over the entire length of said vessel, a pan below the vessel to collect and discharge the cooling medium, an adjustable shaft in said vessel and a scraper hung from said shaft and adjusted thereby with respect to the interior surface of said vessel.

25 30 In testimony that I claim the foregoing as my invention, I have signed my name in presence of two subscribing witnesses.

EINAR HANSEN.
